UNITED STATES PATENT OFFICE.

ALEXANDER McDougall, OF DULUTH, MINNESOTA.

SHIP-HATCH.

1,270,428.

Specification of Letters Patent. Patented June 25, 1918.

Application filed September 22, 1917. Serial No. 192,690.

To all whom it may concern:

Be it known that I, ALEXANDER McDougall, a citizen of the United States, residing at Duluth, in the county of St. Louis and 5 State of Minnesota, have invented certain new and useful Improvements in Ship-Hatches, of which the following is a specification, reference being had therein to the accompanying drawing.

10 This invention consists of certain novel and useful improvements in ship hatches and the method of making same water and air tight and relates particularly to a class of ship constructed with a view of receiving the 15 wash of waves upon her deck while at sea and upon which type of ship a number of patents have been recently issued to me.

The specific form of hatch and coaming to which this invention is peculiarly applicable is such as that disclosed in my United States Patent Number 1,199,802, dated Oct. 3rd, 1916 and entitled Ship hatch.

20 The principal object of the invention is to provide means and disclose a method by 25 which such hatches may be made quickly and securely water and air tight, not only for the purposes of ordinary maritime commerce, but to provide against sinking of the ship in the event of accident or damage by 30 acts of warfare.

Other objects and advantages of the invention will appear in the further disclosure of same.

Referring to the accompanying drawings 35 forming part of this application and in which like reference characters designate like parts:

Figure 1 is a top plan view of a fragmental portion of the deck of a vessel equipped 40 with the general form of hatch cover and coaming disclosed in my patent above referred to, one of the hatch covers being partly removed from its respective opening,

Fig. 2 is a vertical sectional athwartships 45 view through a portion of one of the hatch covers and the hatch coaming,

Fig. 3 is a similar view taken fore and aft the hatch and centrally thereof illustrating the manner of adjusting the hatch cover, 50 and

Fig. 4 is a similar though fragmental view illustrating the manner of applying the hook for moving the hatch covers fore and aft.

1 represents the deck of the vessel and 2 55 the hatch openings therein, which are common in the art.

Securely fixed to the deck 1 and about the edges of the hatch openings 2 is the low flat metal bar 3 forming the hatch coaming, the upper face of which is inclined downwardly 60 away from the hatch around the entire surface thereof and provided with a plurality of hatch bolt holes 4 which are spaced to register with similar holes 5 in the hatch cover 6 when the latter is in place, the holes 65 in the cover, being plain straight holes, and those in the coaming, being internally screw threaded for receiving the similarly formed hatch bolts 7, and each hole in the coaming being provided with a drain slot or limber 70 8, all of which construction is similar to that known in the prior art, except that the packing 9, which is let into the upper face of the hatch coaming 3, is located upon the inner side of the row of hatch bolt holes, 75 instead of upon the outer side as shown in my patent above referred to, and which location herein disclosed forms an important part of my present invention. In practice the placing of fixed strips of rubber outside 80 of the row of holes has proven to be defective in that it becomes possible under certain conditions for air or water to work through the holes about the bolts and eventually into the hatchway, but when the packing is placed 85 inside of the row of holes, such action of the water or air becomes impossible.

Within the upper inclined face of the coaming 3, close to the inner edge of the line of bolt holes 4 and continuous around 90 the entire hatch is formed a groove or channel 20, it being preferably wider at the bottom than at the top and of a size to snugly hold the round cord or packing 9 and which latter is of a size to be readily removed at 95 any time and replaced by a new one.

The groove 20 is preferably of a size and shape similar to that known in the art in which rubber or other packing material is permanently embedded, but, as before stated, 100 its location and relation to the bolts 7 is one of the essential features of my present invention.

Within this groove is removably placed the cord or packing 9 which is preferably 105 round in form and which may be a common rope suitable for the purpose or a specially prepared packing, it being placed in the groove with the ends thereof abutting each other. The groove being angular in form 110 and the packing round permits of greater scope of the elastic property of the packing.

and when damaged or becoming inefficient from any cause may be quickly removed and replaced by a new one.

To further insure a tight joint between the coaming and the hatch cover and to provide against the necessity of having to force compressed air within the hull of the vessel when danger of sinking occurs, which would require an exceptionally tight hatch joint, I have provided a smaller flexible cord 10, such as cotton or the like, which is placed between the hatch cover and the coaming and inside of the packing 9, as illustrated in Fig. 2 of the drawings. This cord would ordinarily be put in place after the cover is positioned over the coaming and as is obvious may be so placed by holding one end fixed and passing the other around the entire hatch and drawing it tightly into the crack between the cover and the coaming until the two ends are crossed one over the other when the hatch bolts 7 are put in place and the cover screwed tightly upon the cord and the packing. As a still further precaution against leakage of air or water, I have illustrated a second loose and larger cord 11 which may be placed in position after the hatch bolts have been applied and which are pinched simultaneously with the smaller cord 10 and the packing 9 when the bolts are screwed home.

It is evident that with care the cord 10 might be placed about the coaming before the hatch cover is drawn into position, but, in practice, I prefer to employ the method first described.

Adjacent the sides of the hatch coaming 3 across the ends of the hatches and in a continuous line intermediate of the hatches, is securely fixed to the deck 1, either by riveting or bolting thereto, a plurality of guide pegs 12. These pegs are preferably cylindrical in shape and are slightly round on top to form as smooth and yieldable engagement as possible with the hatch covers when contacting same and are spaced a slight distance outside of the normal path of the hatch cover. These pegs act as guides to the hatch cover to prevent them becoming materially dislodged from proper alignment either while upon the coaming or when being moved to or from same. In the preferred arrangement of hatches as illustrated in Fig. 1 the distance between the hatch opening is somewhat greater than the width of a single opening and I have illustrated in such space adjacent one hatch opening two pegs 13-13 as securely fixed to the deck 1 and which act as stops for the hatch cover, which is drawn against same, to prevent the cover from being entirely withdrawn from the coaming for obvious reasons, and there are also fixed to the deck and in close proximity to the edge of each hatch toward which the cover is drawn when closing the

hatches, two similar pegs 14, they acting as stops to the hatch cover for properly positioning same.

As a means for drawing the hatch covers to or from the coaming, I have illustrated the clip 15 fastened centrally to each forward and after edge of the hatch cover, the free end of said clip being inclined upwardly from a plane with the top of the cover and having a suitable hole 16 therethrough to admit of ready application of the line-hook 17 and by which the cover may be manipulated fore and aft of the vessel.

Adjacent each forward and after edge of the coaming 3 and centrally thereof is securely riveted to the deck 1 a small piece of plate 18 having a hole 19 therethrough which hole should approximately register with the hole 16 in the corresponding clip 15 above same when the hatch cover is in place on the coaming. When these holes do not properly register a small hand bar such as illustrated at 21, which may be a bar for the purpose or the shank end of the wrench used in applying and removing the hatch bolts, is inserted through the hole 16 in the hatch cover clip and the end engaged within the hole 19 in the plate 18.

When thus applied, a comparatively slight movement of the bar in any desired horizontal direction will move the hatch cover slightly and by which the holes in the cover and the coaming are easily made to properly register for application of the hatch bolts.

In this manner the clips 15 are made to perform a double function both of which are very essential in the practical manipulation of the hatch covers.

It is known in the art that in the successful use of a large hatch cover operated as a single unit some fore and aft supports in the hatchway become necessary and these I have illustrated at 22 as removable strongbacks and which may be installed or removed as desired.

While I have illustrated the flexible loose cords which are not let into the coaming as being in combination with a larger packing cord which is let into the coaming it is evident that either separately might prove sufficient for the conditions in hand and that largely depending upon the service in which the vessel was engaged, but it has proven in practice to be very desirable to use the loose cords within the joint when a permanently fixed rubber packing is used as in my former patent above referred to.

Thus I have provided a simple, cheap and efficient form of water and air tight hatch, the same being exceedingly inexpensive, easy of application and adjustment and one that restores to the deck of the ship when bolted in place a uniform yieldable structure over the entire area of the deck and forms little

or no obstruction to the water when the deck is awash.

While I have shown the hatch cover as being composed of a single metal plate, it is 5 evident that the same may be built up of a plurality of plates if desired and that various other modifications of the specific construction illustrated and within the scope of the invention may be resorted to without de- 10 parting from the spirit thereof.

Having thus described my invention, what I claim as new and desire to secure by Letters Patent, is:

1. In a ship hatch the combination with a 15 low flat hatch coaming having an upper surface inclined downwardly from the hatch opening, a packing embedded within such surface and a hatch cover, of hatch bolts passing through the cover and engaging the 20 coaming outside of the packing.

2. A ship's hatch comprising in combination a low flat coaming about the hatch, said coaming having an upper surface inclined downwardly from the hatch and carrying a 25 packing embedded within the inclined surface, a hatch cover covering the entire opening and the upper surface of the coaming, bolts passing through the hatch cover and into the coaming outside of the packing and 30 a row of upstanding guiding pegs fixed to the deck adjacent each end of the hatch and intermediate of same for guiding the hatch covers as they are moved to and from the hatches.

3. A ship's hatch comprising in combination a low flat coaming, said coaming having an upper surface inclined downwardly from the hatch and carrying a resilient packing embedded within the inclined surface, a 40 hatch cover for co-operatively engaging the coaming, bolts passing through the cover and into the coaming outside of the packing, flexible removable cords placed intermediate of the cover and the coaming, one be- 45 tween the packing and the innermost edge of the coaming and the other outside of the bolts and adjacent the outer edge of the hatch, means for sliding the hatch cover to and from the hatch and means for guiding 50 the cover as it is being operated.

4. The combination with a ship's hatch, having a low flat coaming about the opening thereof, said coaming having an upper surface inclined downwardly from the hatch, 55 a resilient rubber embedded within the coaming, a slidable cover for co-operative engagement with the coaming and bolts arranged outside of the resilient packing for forcibly holding the cover down upon the 60 innermost corner of the coaming and the packing, of a removable flexible cord inserted intermediate of the cover and the coaming in such a manner as to be impinged simultaneously with the packing substantially 65 as described.

5. The herein described method of making a water and air tight hatch cover joint in which a space occurs intermediate of the cover and the coaming, of placing a flexible cord within such space and wholly about 70 the hatch before binding the hatch cover and coaming together whereby the cord becomes tightly impinged intermediate of the cover and coaming and effectually calks such joint. 75

6. The herein described method of making a water and air tight hatch cover joint in which a graduated space occurs intermediate of the cover and the coaming and the two held together by screw bolts, of holding 80 at one corner of the hatch one end of a flexible cord, passing around the hatch with the opposite end of the cord and having it snugly fit into the graduated space on all four sides of the hatch, then crossing the 85 ends of the cord at the first mentioned corner of the hatch and drawing the cover down tightly upon the cord by means of the screw bolts.

7. In a ship's hatch, the combination with 90 a low flat hatch coaming having an upper surface inclined downwardly from the hatch opening, of an angularly shaped groove formed in the upper surface of the coaming and entirely around the hatch, a 95 removable round packing within the groove, a row of bolt holes adjacent the groove and upon the outer side thereof in respect to the hatchway, a hatch cover having holes regis- 100 terable with the holes in the coaming and bolts in the holes for holding the cover tightly upon the coaming and the packing.

8. In a ship's hatch, the combination with 105 a low flat hatch coaming having an upper surface inclined downwardly from the hatch opening, a continuous groove formed in said surface wholly about the hatch and a hatch cover, of a removable round pack- 110 ing cord within said groove and hatch bolts arranged adjacent to and outside of the packing for holding the cover tightly against the packing and the coaming.

9. The combination with a ship's hatch, having a cover operated as a single unit and held in place by hatch bolts, of a clip fixed 115 to the edge of the cover and having a hole therethrough for engagement either with a hook and line for moving the cover on and off the coaming, or a hand bar for final adjustment of the cover before applying the 120 bolts.

10. In combination, a hatch coaming having an upper face inclined downwardly away from the hatch, a hatch cover operated as a single unit normally resting upon 125 the innermost edges of the coaming, regis- terable holes in the coaming and in the cover, a clip having a hole therethrough fas- tened centrally to each forward and after edge of the hatch cover by which the cover 130

- may be drawn to or from the coaming, a plate fixed to the deck upon which the hatch is located adjacent the coaming on each forward and after side thereof and beneath the 5 clips, and holes in the plates which substantially register with the holes in the clips, whereby a hand bar may be placed through the hole in one of the clips and the lower end engaged in the hole in the corresponding plate for moving the hatch cover.
- 10 11. In combination, a hatch coaming having an upper face inclined downwardly away from the hatch and having bolt holes therein, a hatch cover operated as a single unit, normally resting upon the innermost edges of the coaming and having holes therein registerable with the holes in the coaming, a clip having a hole therethrough, fastened centrally to each forward and 15 after edge of the hatch cover and by which the cover may be drawn to and from the coaming, a hole supported by the deck upon which the hatch is located adjacent the coaming on each forward and after side 20 thereof beneath the clips and substantially registering with the holes in the clips,
- 25

whereby a hand bar may be placed through the holes in the clips and engaged in the hole on the deck for adjusting the hatch cover to place.

30

12. In combination a ship's hatch coaming having bolt holes therein, a hatch cover operated as a single unit normally resting upon the coaming and having holes therein registerable with the holes in the coaming, a clip having a hole therethrough fastened centrally to each forward and after edge of the hatch cover by which the cover may be drawn to and from the coaming or adjusted while upon the coaming, a hand bar extendible through the holes in the clips, means below the clips and supported by the deck of the ship for engagement with the end of the hand bar to hold same against movement while adjusting the hatch cover to its proper position.
